ABRAHAM GOLDBERG
INVENTOR

W. M. G. J. G.
WITNESS:

BY *Victor J. Evans*

ATTORNEY

UNITED STATES PATENT OFFICE.

ABRAHAM GOLDBERG, OF NEW YORK, N. Y.

TOOTHBRUSH.

Application filed October 10, 1927. Serial No. 225,283.

This invention relates to improvements in tooth brushes and has particular reference to a combined tooth brush and massage device.

The primary object of the invention resides 5 in a massage device embodied in a novel form of tooth brush by which the gums of the human mouth may be massaged during the brushing of the teeth to stimulate the tissues thereof, and keep the same in a healthy condition.

Another object of the invention is to provide a combined tooth brush and massage device which cleans and massages both the front, back and crown of the teeth and gums 15 simultaneously by a single operation.

A further object is the provision of a tooth brush having a brush head of U-shape in cross section, the bottom side edges of the head having removable massage elements whereby the 20 same may be replaced when worn or other massaging applicators such as cotton or gauze may be substituted.

A still further object is to construct a combined tooth brush and massage device which 25 is simple of construction, inexpensive of manufacture, and easy and thorough in use.

With these and other objects in view, the invention resides in certain novel construction and combination and arrangement of parts, 30 the essential features of which are herein-after fully described, are particularly pointed out in the appended claims, and are illustrated in the accompanying drawing, in which:—

Figure 1 is a perspective view of my combined tooth brush and massage device.

Figure 2 is a vertical longitudinal sectional view therethrough.

Figure 3 is a vertical transverse sectional view on the line 3—3 of Figure 2.

Figure 4 is an enlarged detail vertical sectional view of the massage element.

Figure 5 is a fragmentary perspective view showing a modified form of massage element.

Referring to the drawing by reference characters, the numeral 10 designates my combined tooth brush and massage device in its entirety which includes a U-shaped head or brush back 11 from which a handle 12 extends. The brush back and handle are formed of the 45 same materials such as celluloid, bone, hard rubber or the like. However, the handle and brush back may be of different materials suitably joined together without in any way departing from the spirit of my invention. The brush 50 back supports inwardly extending bristles 13 which define a U-shaped passage for the teeth.

during the brushing of the same. The brush back may be provided with suitable openings 14 which open on opposite sides thereof to allow for the circulation of air through the 60 bristles to ventilate the same to keep them in a sanitary condition and for drying.

The free edges of the side walls of the brush head are curved slightly inward and enlarged in thickness as at 15, and have round recesses 65 16 opening onto the outer edge and extending the full length of the brush head. Seated in the round recesses 16 are the longitudinal circular heads 17 of yieldable massage elements 18. The free surfaces of the massage elements 70 are undulated as at 19 and which constitutes the massage surfaces of the elements. The same extend inwardly of the inner side walls of the brush head to protect the gums from 75 injury thereby.

In use, the brush is applied over the teeth so that the teeth are received in the passage defined by the bristles, whereupon the user proceeds to reciprocate the same in the customary manner. By reason of the shape of the 80 brush both sides of the teeth are cleansed simultaneously as are the outer bights of the teeth. During the brushing operation, the massage elements 18 engage the opposite sides of the gums at their joinder with the teeth 85 which massage action keeps the gum line clean and healthy and has a tendency to prevent and cure diseases of the gums.

Should the massage elements 18 become worn or lose their flexibility, the same may 90 be removed by sliding them longitudinally from the recesses 16 and new ones substituted therefor. The friction between the massage elements and the brush head prevents accidental shifting of the massage elements during 95 the massaging operation.

In Figure 5 of the drawing, I have shown a slightly modified form wherein a cotton wad 20 may be seated in the recesses 16 in lieu of the massage elements 18. These wads 100 are commonly used in the dental profession and are exceptionally inexpensive so that fresh massage elements might be used for each massage operation at a small cost.

From the foregoing description, it will be 105 manifest that I have shown and described an article by which the massage of the gums will be encouraged as the operation is performed simultaneously with the brushing of the teeth. It is a common habit for persons to 110 neglect the massage of the gums as it requires additional time and a separate massage de-

vice other than a tooth brush. By the use of my article, the teeth and gums may be kept in a healthy condition.

While I have described what I deem to be the most desirable embodiment of my invention, it is obvious that many of the details may be varied without in any way departing from the spirit of my invention, and I therefore do not limit myself to the exact details 10 of construction herein set forth nor to anything less than the whole of my invention limited only by the appended claims.

What is claimed as new is:—

1. A tooth brush comprising a U-shape 15 head having grooves provided in its free longitudinal edges, inwardly extending bristles on said head and yieldable massage elements provided with ribs for reception in the respective grooves.

20 2. In combination with a tooth brush hav-

ing a U-shape head, inwardly extending bristles on said head, and inwardly extending yieldable massage strips carried by said head along the longitudinal edges thereof.

3. A tooth brush comprising a head of U- 25 shape in cross section having a manipulating handle extending therefrom, bristles extending inwardly from the inner walls of said head, the free ends of the bristles carried by the opposed side walls of said head terminating in spaced relation, and massage strips carried by the longitudinal free edges of said head, whereby the gums of the human mouth may be simultaneously massaged during the 30 cleaning of the teeth by the bristles of the brush head when moved over the teeth.

In testimony whereof I have affixed my signature.

ABRAHAM GOLDBERG.
